UNITED STATES PATENT OFFICE.

EASON L. SLOCUM, OF PAWTUCKET, RHODE ISLAND.

FIRE-ALARM APPARATUS.

SPECIFICATION forming part of Letters Patent No. 351,075, dated October 19, 1886.

Application filed November 18, 1885. Serial No. 183,160. (No model.)

To all whom it may concern:

Be it known that I, EASON L. SLOCUM, a citizen of the United States, residing at Pawtucket, in the county of Providence and State of Rhode Island, have invented certain new and useful Improvements in Fire-Alarm Apparatus; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates to improvements in fire-alarm apparatus, said improvements being more particularly adapted to be combined with the "Gamewell" system; and it consists, essentially, in the combination, with the detent lever and wheel thereof, of one or more electro-magnets arranged within the box, and connected electrically with the detent-lever, whereby an electric current passing through the magnets withdraws said lever from its notched wheel, thereby causing the clock-train to actuate the striking mechanism and give an alarm, all as will be more fully hereinafter set forth and claimed.

The object of my present invention is to provide fire-alarm boxes with simple and efficient means whereby an alarm or signal may be given independently of the usual operating hook or lever, which latter can be manipulated only at the box and after the door thereof is opened.

With the aid of my invention the mechanism is set in motion by means of an electric current passing through one or more magnets, whose armature is connected with the detent-lever, the current being produced by means of a battery or other suitable generator conveniently arranged with reference to the box, the battery in turn being connected with one or a number of sub-stations to form a local fire-alarm district. It is obvious that a person at any one of said sub-stations by simply pressing the button thereof closes the electric circuit, thus charging the magnets and attracting the armature connected with the detent-lever, the latter thereby being withdrawn from the notched wheel and permitting the spring or clock train to operate the striking mechanism, located in a signal-tower, as usual.

In order to illustrate my improvements, I have prepared the accompanying three sheets of drawings, in which—

Figure 1, Sheet 1, represents a front view of a Gamewell fire-alarm box, with its two doors removed, showing the detent-lever connected with electro-magnets by means of compound levers adapted to vertically lift the former-named lever from its notched wheel. Fig. 2, Sheet 2, is a partial front view of the same, showing the detent-lever and electro-magnets connected by means of a single lever or arm, to which the armature is attached. Fig. 3 is a similar view showing the electro-magnets located above the detent-lever, the armature in this case being directly connected with or attached to the said lever. Fig. 4 is a partial transverse sectional view of the lever and detent-wheel, enlarged, showing a roll mounted on the end of the armature-lever bearing against the under side of a lug extending in front and forming a part of the detent lever corresponding to Figs. 1 and 2. Fig. 5, Sheet 3, is a vertical sectional view, showing a battery and sub stations, electrically connected with the magnets for the purpose of releasing the detent-lever from its notch; and Fig. 6 represents a plan view, reduced, of a portion of a general fire district, showing an arrangement of sub-stations to form local fire-alarm districts, in which a Gamewell fire-alarm box constitutes the center thereof.

The following is a more detailed description of the invention, including the manner of its construction and operation.

R, again referring to the drawings, designates the fire-alarm box of the Gamewell type as a whole, mounted on a pole or other suitable support, and electrically connected with a bell or signal tower, as usual. A is the inner chamber of said box, within which the operating mechanism is arranged, the latter comprising the clock-train H, or other suitable spring-actuated gearing, the detent-lever E, pivoted to the frame a', and having a lug, i², which engages a notch formed in the rim n of the wheel K. The free end e² of said lever is adapted to engage the armature of the magnets a when the former is disengaged from the wheel, said parts e² and a when thus connected serving as a "cut-out" to prevent the alarm then being given from the box to be electric-

ally communicated to any other alarm-box included in the general district.

F is a hook or lever extending through the inner door, (in front thereof,) and pivoted to the frame a', the rear end of the hook being adapted to engage the end e² of the lever E, before described, and release the latter from the wheel K, when the projecting portion of the hook is depressed.

10 All the foregoing-indicated elements being substantially embodied in the Gamewell patents, therefore a further description thereof is not deemed essential to this specification.

15 The following relates more particularly to the improvements forming the present invention.

B B indicate electro magnets of ordinary construction, secured within the chamber A, Fig. 1.

20 C designates a lever pivoted at c' to the back of the box, the lower end of said lever having a piece of soft iron, c, secured thereto, which forms the armature for the magnets.

C' is a lever pivoted at c² to the frame a', 25 said lever at its upper end being provided with an anti-friction roller, c³, which bears against the under side of a projection, i, formed on the front of the detent-lever E, (see Fig. 4,) the opposite or lower end of said lever C being connected to the upper end of the lever C by means of the short link d, the two when thus united forming a compound lever.

m' is a stop, which serves to limit the movement of the levers, while a spring, m, at the 30 same time retains the parts in the normal position, as clearly shown in said Fig. 1.

In Fig. 2 a simple lever, c⁵, is represented, the same being pivoted to the frame a' at c⁶. The inner or short arm thereof is provided 40 with a roll, c⁸, an armature, c, being secured to the long arm of the lever and further provided with a stop, m', and spring m, as before described.

45 In lieu of the armature-carrying levers C c⁵, I have shown in Fig. 3 the armature as attached to the detent-lever E by means of a rod, c⁴, the magnets B therefor being mounted in a small chamber, B', at the top of the box R.

I do not claim herewith the modification 50 just described, as the same will form the subject of another application for Letters Patent to be filed by me in the United States Patent Office.

V, Fig. 5, indicates an electric battery or 55 generator of electricity, which connects with the magnets B by means of conducting-wires t.

w designates sub-stations, or push-buttons, conveniently located as shown, each being connected with the battery and forming an electric 60 circuit when the button is pressed upon, as is well known to an electrician.

By means of this device each fire-alarm box R is adapted to form the center of a local and independent fire district, within which any 65 number of sub-stations w may be included and connected, from each of which a signal may be given. The several boxes, R, in turn may

be still further electrically connected to form a general or municipal fire district having bell-towers, &c., as usual.

70 The operation of withdrawing the lever E from the notched rim of the detent-wheel K by means of the invention claimed herewith is as follows: Assuming, first, that the box or station R is electrically connected with the signal 75 or bell tower, and also that one or more electro-magnets, B, are mounted within said box, and connected with a battery, V, and sub-stations w, substantially as shown and hereinbefore described. Now, in order to give an 80 alarm a person presses the button of a substation, thereby instantly closing the local circuit and charging the magnets B. The attractive force thereof, acting now on the armature c, causes the latter, with its attached lever, to 85 vibrate slightly, which, by means of its connections or levers, withdraws the detent-lever E from the spring actuated wheel K and allows it (the wheel) to make one revolution, which movement is communicated to the signal-wheel H². The spurs thereof at the same 90 time coming successively in contact with the electrically-connected plate h opens the main circuit, (the intervals or spaces of the wheel H² closing the circuit,) thereby sounding a 95 general alarm from the bell-tower, as common to this system. Meanwhile, the finger is removed from the button w, thus opening the local circuit and demagnetizing the magnets B, the lever C, &c., then resuming its normal 100 position by means of the spring m, as indicated in the several figures. Upon the completion of the revolution of the wheel K the lever E again engages the notch of the rim n, assisted by the spring e', the whole now being 105 again in position to send out another alarm.

It is evident that the device hereinafter claimed in no wise prevents an alarm being sent out by a person at the box R, as usual.

110 My improvement is adapted to be combined with any fire-alarm box having a detent-lever adapted to interlock with the operating mechanism. Therefore I do not restrict myself to the particular form and arrangement of the box and its striking mechanism as represented 115 in the drawings. I would not be understood, however, as claiming, broadly, as my invention, a fire-alarm box provided with means for releasing the detent-lever from the detent-wheel through the agency of one or more electro-magnets located in the box and adapted to be operated from a distance to send out an alarm.

Having thus described my invention, what I 120 claim as new, and desire to secure by United States Letters Patent, is—

1. In a fire-alarm box or apparatus of the Gamewell or similar type having means for operating it by hand, as usual, the combination, with the detent-wheel and detent-lever thereof, of one or more electro-magnets, B, mounted within said box, connected with one or more local electric circuits, and a pivoted arm or lever having one end engaging said de-

tent-lever, and the other end of the pivoted lever provided with an armature engaging said electro-magnets B while an alarm is being turned in through the agency of said local electric circuits, substantially as described, and for the purpose hereinbefore set forth.

2. The combination, with a fire-alarm box apparatus adapted to be operated by hand, of an electro-magnet connected with a suitable battery or generator, an arm or lever, C', carrying the armature of said magnet, and means consisting of the pivoted supplemental or compound lever c', and the link d, for connecting said arm with the detent-lever of the fire-alarm mechanism, for the purpose hereinbefore set forth.

3. The combination, with the notched wheel K, and detent-lever E, having a projection, i, of a pivoted arm or lever carrying a roller, c⁸, engaging said projection, and a suitably-connected electro-magnet, B, whose armature is carried by said pivoted arm, substantially as shown, and for the purpose hereinbefore set forth.

In testimony whereof I have affixed my signature in presence of two witnesses.

EASON L. SLOCUM.
